UNITED STATES PATENT OFFICE.

THOREY I. MOEN, OF BELOIT, WISCONSIN.

HEADLIGHT ATTACHMENT.

Application filed August 4, 1927. Serial No. 210,664.

The invention aims to provide a novel and advantageous form of attachment for automobile headlights, of such nature as to prevent the lights from blinding pedestrians or the drivers of approaching vehicles, while giving ample roadway illumination for the driver of the machine equipped with the invention.

With the foregoing in view, the invention 10 resides in the novel subject matter herein-after described and claimed, the description being supplemented by the accompanying drawing.

Fig. 1 is a vertical sectional view showing 15 the invention applied to a headlight.

Fig. 2 is a horizontal sectional view on line 2—2 of Fig. 1.

Fig. 3 is a front elevation, the lens-carrying headlight door being removed.

20 Figs. 4 and 5 are detail sectional views on lines 4—4 and 5—5 of Fig. 1.

In the drawings above briefly described, the numerals 6 denote two vertical walls which are preferably parallel and are adapted 25 for disposition at opposite sides of the usual headlight bulb 7, the rear edges 8 of said walls being curved to correspond with the curvature of the headlight reflector 9. At their lower front corners, these walls are 30 rigidly connected with a plate 10 which projects downwardly therefrom to be clamped between the usual reflector flange 11 and the lens-carrying door 12 of the headlight.

Between the upper ends of the walls 6, is 35 a visor 13 which embodies a rear, horizontal reflector 14 to extend over the bulb 7, and a front reflector 15 which declines forwardly from said reflector 14 and extends in front of the bulb. This visor not only prevents 40 direct forward and upward escape of rays from the bulb, but its reflectors 14 and 15, serve to downwardly reflect rays from said bulb, as will be clear from Fig. 1. Some of these rays strike the reflector 9 and are 45 forwardly and downwardly directed by the latter and some of them strike a second forwardly declined reflector 16 which extends between the walls 6 and is located under the bulb 7. Also, direct downward rays 50 from the bulb, are received by the reflector 16 and directed forwardly and downwardly.

I form substantially triangular openings 55 17 in the rear portions of the walls 6, to permit lateral passage of rays from the bulb 7 to the reflector 9, but to obscure the portions of the bulb which are received in the

openings 17 from the vision of persons facing the machine, I provide rearwardly diverging vanes 18 which are disposed at the front edges of said openings 17. These 60 vanes terminate above the lower forwardly declined edges 17^a of the openings 17, leaving spaces 17^b through which light rays may pass from the bulb 7 to the lower part of reflector 9.

The opposite edges of the mirrors 14 and 15, are received in grooves 19, formed preferably by outwardly stamping upper edge portions of the plates or walls 6, such outward stamping providing the outer sides of 70 these walls with projections 20 extending along their grooved portions. Metal strips 21 extend from one wall to the other and across the upper edges thereof, and the ends of these strips are provided with hooks 22 75 which hook around the outward projections 20. Thus, the reflectors 14 and 15 are effectively held in the grooves 19 and the walls 6 are held against separation.

To secure the reflectors 16 in place, I 80 prefer to provide outwardly stamped portions 23 in the walls 6, producing grooves which receive edges of said reflectors.

A device constructed as or substantially as 85 herein shown and described, may be easily and inexpensively manufactured, may be sold at small cost, may be quickly and easily applied, and when in use, will insure that the rays from the headlights shall be directed forwardly and downwardly, so as to 90 effectively illuminate the roadway for the progress of the machine, while preventing the blinding of pedestrians or the drivers of approaching machines.

On account of existing advantages for the 95 details disclosed, they are preferably followed. However, within the scope of the invention as claimed, variations may be made.

I claim:—

1. In a headlight attachment, vertical walls to straddle the headlight bulb, and a visor at the upper end of said walls to extend over and to entirely cover the bulb and in front thereof, said visor being impervious to light.

2. In a headlight attachment, vertical walls to straddle the headlight bulb, and a visor to extend over and to entirely cover the bulb and in front thereof, said visor having a reflecting surface for downwardly reflecting rays from the bulb.

3. In a headlight attachment, vertical walls to straddle the headlight bulb, a visor to extend over the bulb and in front thereof, and an inclined reflector mounted between 5 said walls for disposition under the bulb to forwardly reflect rays therefrom. 45
4. In a headlight attachment, vertical walls to straddle the headlight bulb, a visor to extend over the bulb and in front thereof, 10 of, said visor having a reflecting surface for downwardly reflecting rays from the bulb, and an inclined reflector mounted between said walls for disposition under the bulb to forwardly reflect rays directed downwardly 15 from said bulb and the reflecting surface of the visor. 50
5. In a headlight attachment, vertical walls to straddle the headlight bulb, and a visor at the upper end of said walls to extend 20 over the bulb and in front thereof, said visor entirely covering the bulb and being impervious to light, said walls having openings below the visor to permit lateral passage of rays from the bulb to the reflector of the 25 headlight. 55
6. A structure as specified in claim 5; together with rearwardly diverging vanes at the front edges of said openings but terminating above the lower edges thereof. 60
7. In a headlight attachment, a pair of vertical walls to straddle the headlight bulb, a vertical plate joined to the lower front corners of said walls and projecting downwardly to be held between the headlight 30 reflector and the lens-carrying door, a bulb 70 visor extending from the upper end of one wall to the upper end of the other wall and embodying a rear horizontal reflector and a front reflector, the latter declining forwardly from said rear reflector, and a second 35 forwardly declined reflector between the walls for disposition under the bulb. 75
8. In a headlight attachment, a pair of vertical walls to straddle the headlight bulb, 40
- a vertical plate joined to the lower front corners of said walls and projecting downwardly to be held between the headlight reflector and the lens-carrying door, a bulb visor extending from the upper end of one wall to the upper end of the other wall and embodying a rear horizontal reflector and a front reflector, the latter declining forwardly from said rear reflector, and a second forwardly declined reflector between the walls for disposition under the bulb, said walls having internal grooves receiving edges of said reflectors, and means tying said walls against lateral spreading to retain the reflectors engaged with the grooves. 50
9. In a headlight attachment, spaced 65 walls having opposed reflector receiving grooves near edges thereof and outward projections along their grooved portions, a reflector having edges disposed in said grooves, and a metal strip extending across the space between the walls and across said edges of the walls, said strip having hooks on its ends hooked around said outward projections. 60
10. In a headlight attachment, vertical 70 walls to straddle the headlight bulb, a visor to extend over the bulb and in front thereof, said vertical walls having openings for disposition at opposite sides of the bulb, said openings having portions extending below the bulb, and vanes diverging rearwardly from the front edges of said openings, said vanes terminating above the lower edges of 75 said openings. 75
11. In a headlight attachment, vertical 80 walls to straddle the headlight bulb, and a visor to extend over the bulb and in front thereof, said walls having openings at opposite sides of the bulb and provided with portions to extend downwardly below the latter. 85
- In testimony whereof I have hereunto affixed my signature.
- THOREY I. MOEN.
